UNITED STATES PATENT OFFICE

150,283

DESIGN FOR A WATCH BOX

Seymour Ackerman, Bell Harbor, N. Y., assignor to Parker Watch Company, New York, N. Y., a partnership

Application July 29, 1947, Serial No. 140,584

Term of patent 3½ years

(Cl. D80—5)

To all whom it may concern:

Be it known that I, Seymour Ackerman, a citizen of the United States of America, and a resident of Bell Harbor, in the county of Queens and State of New York, have invented a new, original and ornamental Design for Watch Box, of which the following is a specification, reference being had to the accompanying drawing, forming part thereof, in which—

Fig. 1 is a top plan view of a watch box embodying my design.

Fig. 2 is a front elevation.

Fig. 3 is an end view, and

Fig. 4 is a perspective view thereof in open position.

I claim:

The ornamental design for a watch box, as shown.

SEYMOUR ACKERMAN.
